UNITED STATES PATENT OFFICE.

EDWARD H. DIETZ, OF AUMSVILLE, OREGON.

FIRE-ESCAPE.

1,296,052.

Specification of Letters Patent.

Patented Mar. 4, 1919.

Application filed April 14, 1917. Serial No. 162,088.

To all whom it may concern:

Be it known that I, EDWARD H. DIETZ, a citizen of the United States, residing at Aumsville, in the county of Marion and 5 State of Oregon, have invented certain new and useful Improvements in Fire-Escapes, of which the following is a specification.

This invention relates to improvements in fire escapes, and more particularly to suspension devices of this character.

The object of the invention is to provide a fire escape which may be attached to the person of the user and whereby he may be automatically lowered without danger of 15 slipping or falling.

Another object is to provide an improved brake for use in connection with apparatus of this character for controlling the speed of the descent of the user.

20 With the foregoing and other objects in view, which will appear as the description proceeds, the invention resides in the combination and arrangement of parts and in the details of construction hereinafter de-

25 scribed and claimed, it being understood that changes in the precise embodiment of the invention herein disclosed may be made within the scope of what is claimed without departing from the spirit of the invention.

30 In the accompanying drawings:

Figure 1 represents a front elevation of a portion of a building showing this improved fire escape in use,

Fig. 2 is an enlarged rear elevation of the 35 fire escape with the casing removed and parts broken out,

Fig. 3 is a horizontal section taken on the line 3—3 of Fig. 2,

Fig. 4 is a longitudinal vertical section 40 taken on the line 4—4 of Fig. 2,

Fig. 5 is a similar view taken on the line 5—5 of Fig. 2,

Fig. 6 is a detail sectional view taken on the line 6—6 of Fig. 2,

45 Fig. 7 is a side elevation with parts broken out showing a slightly different form of the invention, and

Fig. 8 is a front elevation thereof with parts broken out.

50 In the embodiment illustrated in Figs. 1 to 6, a casing 1 is shown, composed of any suitable material preferably of light weight metal, and which is designed to be attached to the body of the user by means of straps 2 and 3, connected with the upper and lower ends of the casing and designed to encircle

the body of the user at points below his arms and around his waist as is shown clearly in Fig. 1. This casing 1 has an opening 4 in its upper end, preferably near its rear wall, 60 which wall is designed to be placed in contact with the body of the user when applied. A partition 6 divides said casing transversely, intermediately of its ends, being preferably disposed midway said ends, although not necessarily so, and forms two chambers 7 and 8.

A frame 50 is mounted within the casing 1 forming a rigid reinforce and support therefor and comprises laterally spaced front uprights 51 and 52 connected at their upper and lower ends by cross bars 53 and 54 with laterally spaced rear uprights 55 and 56. A cross bar 57 connects the two front uprights at a point near their lower 75 ends and a corresponding oppositely disposed cross bar 58 connects the rear uprights 55 and 56.

A front plate 59 is secured to the front uprights 51 and 52 on their inner faces and 80 extends from a point adjacent the upper cross bars 53 to a point adjacent the partition 6, said partition being secured to said plate. This plate 59 is formed of any suitable metal of a thickness sufficient to support 85 the parts to be carried thereby and which will be hereinafter more fully described.

The casing 1 is secured to this supporting frame by any suitable means and serves to conceal and protect the parts disposed 90 therein.

In the lower chamber 8 is revolvably mounted a reel 9, the journals 10 of which are mounted to rotate in bearings 11 carried by the front and rear cross bars 57 and 58 of the frame 50. A belt or suspension element 95 in the form of a strap 12, of webbing, leather or other suitable material, is wound on said reel, being attached at one end thereto and having its other end passed upwardly through a tube 13, disposed longitudinally in the rear of the chamber 7 and passing through the partition 6, as is shown clearly 100 in Figs. 4 and 5.

This belt 12, after leaving tube 13, passes 105 between two rollers 14 and 15 which are provided with intermeshing cog wheels 16 and 17. The belt after passing through these rollers, passes around a drum 18 which is provided at one end with a gear wheel 19 110 which meshes with cog wheel 17 so that all danger of the belt slipping during its pas-

sage through the rollers is prevented. After leaving the drum 18, the belt passes under a roller 20 as is shown clearly in Fig. 5. From roller 20 it passes out through the opening 4 in the top of the casing and is provided at its end with a loop 21 or other attaching device for securing the belt to a fixed support which is here shown in the form of a hook H carried by the window frame of the 10 building, but obviously it may be connected with any other support in the room.

The shaft 22 of drum 18 has fixed to its opposite end a bevel gear 23 which meshes with a similar gear 24 of smaller size. This 15 bevel gear 24 is fixed to a shaft 25 mounted to turn in a bearing 26 carried by the front plate 59 of frame 50, and in a bearing carried by a bracket 27 which projects inwardly from said plate 59 and has an upstanding 20 arm 28 which forms a support for one end of shaft 22 as well as for shaft 25, (see Fig. 4). A worm gear 29 is also fixed to shaft 25 and meshes with a worm 30 on a shaft 31 supported in a bracket 32 which projects 25 inwardly at right angles from the plate 59 and the shaft 31 has its other end journaled in a bracket 33 carried by said bracket 27 (see Figs. 2 and 4). The pitch of the worm screw 30 is coarse enough to permit gear 29 30 to drive the worm shaft.

The braking mechanism for this apparatus comprises a disk 34 having a sleeve 35 projecting from its inner face and mounted to slide on and revolve with the shaft 31. Fixed to said sleeve on the enlarged portion 36 thereof is a governor, here shown in the form of two resilient strips 38 and 39 engaged at one end to opposite sides of the sleeve member 36 and at their other 40 ends secured to a collar 40 fixed to shaft 31 and which is preferably adjustable thereon and secured by a set screw 41. Weights 42 are carried by these springs on the outer faces thereof midway their ends in the usual 45 manner and operate to distend the springs when the shaft 31 is rapidly rotated and thereby draw disk 34 inwardly for a purpose now to be described.

Cooperating with this disk 34 is a brake 50 member 43 of U-shape form. This U-shaped brake member 43 straddles the shaft 31 and is provided at the free ends of its arms with braking elements 44 composed of any suitable friction material, preferably leather. 55 These elements 44 are designed to engage the inner face of disk 34 preferably near its periphery as is shown clearly in Fig. 2 so that when the shaft is rotated rapidly, the expansion of springs 38 and 39 will 60 cause said disk to move inwardly against said elements 44 and thereby exert a braking action on the shaft 31.

The cross bar 45 of this brake member 43 is secured to the inner face of the free 65 end of one arm 46' of a bell crank 46 which

latter is fulcrumed on the inner face of plate 59 in a plane below shaft 31 as is shown clearly in Fig. 2, the arm 46' thereof extending vertically upward between the inner face of plate 59 and shaft 31. The other 70 arm 47 of said bell crank extends in a horizontal plane and is engaged at its free end on the lower face thereof by a set screw 48 mounted in the bracket 49 projecting laterally from plate 59. This screw is designed 75 for controlling the braking engagement of the elements 44 with disk 34, it being obvious that the raising of set screw 48 will operate to elevate arm 47 of the bell crank thereby causing the arm 46' to move outwardly and force the braking elements 44 carried by the member 43 into close engagement with the disk 34. It will also be obvious that the lowering of this set screw will have the reverse effect and reduce the braking 80 action between the elements 44 and the disk 34.

As shown clearly in Figs. 2 and 3, the arms of the U-shaped braking member 43 have their terminals extended laterally toward disk 34 so that the operation of the bell crank as above described will have the effect set forth.

From the above description it will be understood that when this improved device is 95 to be used that the loop 21 will be engaged with a supporting object here shown in the form of a hook H carried by the window casing and after being so engaged, the casing 1 may be connected to the wearer by 100 placing the straps 2 and 3 around his body beneath his arms and at the waist respectively as is shown clearly in Fig. 1, the casing 1 being disposed in front of the wearer so that the strap or belt 12 will be positioned for convenient grasping by the hands of the user if it should be found necessary. The wearer may then readily descend, the belt being fed slowly out of the casing 1 and passing from reel or drum 9 through 110 tube 13 and between the rollers carried in chamber 7 in the manner above described which causes the rotation of shaft 31 and under the action of the brake thereon, permits the slow descent of the user of the device, the speed of his descent being controlled by the braking action between the elements 44 and the disk 34 which as above set forth, may be set at any desired position by means of the set screw 48.

After the descent is made, the device may be detached from the wearer and the belt 12 again wound up on the reel 9 and be again ready for use. If desired or found necessary, this belt 12 may be severed and 125 a new belt may be applied to the reel to replace the one destroyed.

In the form shown in Figs. 7 and 8, the apparatus is exactly like that of Figs. 1 to 6 except that the reel 9 is dispensed with, 130

and the belt 12 is folded within the chamber 8 to provide for the use of a longer belt than would be possible when applied to a reel, this being especially desirable when the 5 device is used in the descent made from high buildings. In this form of the device, the casing is provided at its bottom with a downwardly opening closure 60 held in place by a suitable bearing indicated at 61 which 10 may be readily opened to release the belt. A weight 62 is connected with the lower end of the belt as is shown clearly in Fig. 8, and when the device is applied for use the closure 60 is opened and the weight 62 15 will cause the belt to drop downwardly to the extreme limit of its length and permit the casing to pass downwardly thereover in the manner above described, the belt being threaded through the rollers and the descent of the casing thereon being thus retarded and its speed controlled.

From the foregoing description, taken in connection with the accompanying drawings, the advantages of the construction and 25 of the method of operation will be readily apparent to those skilled in the art to which the invention appertains and while I have described the principle of operation of the invention together with the device which I 30 now consider to be the best embodiment

thereof, I desire to have it understood that the device shown is merely illustrative and that such changes may be made as are within the scope of the claimed invention.

I claim:

A fire escape of the class described comprising a casing having a transverse partition dividing it into two compartments, a tube in the upper compartment extending through said partition, a reel revolvably 40 mounted in the lower compartment, rollers located above said tube and carrying intermeshing gears, a drum having a gear meshing with one of the roller gears, a guide roller contacting with said drum, a suspension element connected at one end with said reel and wound thereon with its other end passed upwardly through said tube between said rollers around said drum, under said guide roller and out of the casing, means 45 for connecting said element to a support, and retarding means for said element operated by said drum.

In testimony whereof I affix my signature in presence of two witnesses.

EDWARD H. DIETZ.
